UNITED STATES PATENT OFFICE.

HENRY McCOLLUM AND JOSEPH PARR, OF NEW YORK, AND ALEXANDER CRUMBIE, OF BROOKLYN, NEW YORK.

BAKING FURNACE AND OVEN.

SPECIFICATION forming part of Letters Patent No. 365,929, dated July 5, 1887.

Application filed June 26, 1886. Serial No. 206,341. (No model.)

To all whom it may concern:

Be it known that we, HENRY McCOLLUM, JOSEPH PARR, and ALEXANDER CRUMBIE, the first two residing in the city of New York, in 5 the county and State of New York, and the last residing in Brooklyn, in the county of Kings and State of New York, have invented a new and useful Improvement in Baking Furnaces and Ovens; and we hereby declare that 10 the following is a full, clear, and exact description of the same, reference being had to the accompanying drawings, and the letters and figures marked thereon, which form a part of this specification.

15 The invention consists in the combination of certain forms of furnaces and flues, herein-after described and shown, with any known form of the reel-oven; and its object is to secure a better circulation of the heat in the 20 oven, and to produce a baking both by the direct contact of the products of combustion with the goods to be baked and also by the radiation of heat from the interior surfaces of the walls of the oven, and to so construct our 25 furnace and oven as to economize in the space required.

In the accompanying drawings, Figure 1 is 30 a longitudinal vertical section of the invention. Fig. 2 is a vertical cross-section of the same on line 2 2 of Fig. 1, and Fig. 3 is a horizontal 35 sectional view on the line of the damper *g*.

Similar letters refer to similar parts in all the figures.

40 *A* is a furnace and oven wall, which is preferably made of brick.

45 *a a'* are two fire-places, the doors opening into which are in the side of the structure enclosing the furnace and oven. Below the fire-places are the grates and underneath these the 40 ash-pits.

50 *b b'* are two open spaces or chambers above the fire-places. The fire-places and the chambers above them run across the furnace structure from side to side, being parallel with the axis or shaft of the reel-frame. This manner of arranging the furnaces enables me to construct the entire furnace and oven in a small space. We prefer to make the brick-work above these chambers in the arched manner 55 shown in Fig. 1, as this adds greater strength

to the furnace-wall itself. Each of these air-chambers has a flue connected with it at the back and passing up through the wall of the furnace and connecting with the chimney. These flues are opened or closed by means of dampers *e e'*, which are regulated by rods and levers in any well-known manner, as shown.

55 *e* is a flue connected with the top of the air-chamber *b*, and passes up and around the side or back of the oven, and is connected with the oven at the top through the openings *f f*. This flue *e* is opened or closed by the damper *g* and regulated by rods and levers in any well-known way, as shown. The baking-chamber itself is connected with the chimney by a flue opening, preferably, into the upper part of the baking-chamber, as shown in Fig. 1. This flue is opened or closed by a damper in any well-known way. During the operation of baking the flue is generally closed.

60 *h* is a hot-air chamber connected with the chamber *b'* by the flue *i*, as shown. This hot-air chamber may or may not be connected with the chimney by a flue. In the drawings no such flue is shown. If the operator desires to 65 allow the products of combustion to escape from the chamber *h*, he can do so by opening the damper *c'*, which will allow the products of combustion to pass off not only from the chamber *b'*, but also from the chamber *h*, which 70 two chambers are connected by a large opening and are substantially one continuous chamber. The object of the chamber *h* is to enable 75 the heat to be radiated into the oven more readily, and through a more extended part of the oven-wall. A further advantage is the saving in the amount of brick-work required to construct this part of the oven.

80 *j* is the reel-frame of the oven. It consists of a central cylinder revolving upon a shaft, 85 passing through the middle of the oven, the said cylinder having projecting arms upon which the baking-pans are pivoted, as shown in Fig. 1. The central cylinder also has flanges 90 projecting from the circumferential edges of its two heads or drums out to the walls of the baking-oven, as shown in Fig. 2. The oven itself is made as nearly circular in form as possible. We prefer this form of reel-oven 95 having a central revolving cylinder, though 100

we do not claim it as part of our invention. Our form and arrangement of furnaces and flues are peculiarly well adapted to be used with this form of reel-oven.

5 *h* is the door opening into the oven, through which the goods to be baked are introduced, and through which they are removed after the baking is finished. We prefer to make the upper side of the doorway beveled, as shown 10 in Fig. 1. The object of beveling the upper side of the doorway is that the operator can see more easily into the oven and has a wider range of view. Moreover, the opening on the inner side of the door may be made smaller, 15 and thus less heat allowed to escape from the baking-oven through this door. Again, such heat as does escape through this door is thus enabled to pass directly upward and escape the eyes of the operator.

20 During the operation of baking in such a reel-oven as is shown and described herein the goods are being constantly introduced into or removed from the oven, so that the door of the oven is open most, if not all, of the time.

25 There is a current of heat continually escaping from the oven through this door. With the old form of oven-doorway the operator, who was compelled to do his work directly in front of the doorway was greatly hindered in his

30 work by this escaping heat, which would strike him in the face, and he would become exhausted in a comparatively short time, so that he would have to be relieved. By beveling the doorway, as already described, I am not only 35 enabled to make the doorway itself smaller, and thereby diminish the amount of heat that is lost in this way, but I give such a direction to the escaping current of heat that it no longer interferes with the operator in his work. In 40 this way I economize in fuel and labor.

Our invention operates as follows: While the fires are being started in the furnaces, the damper *g* is closed, thus preventing the dust and smoke from passing into the flue *e*, and 45 the dampers *c c'* are opened, and thus the dust and smoke are allowed to escape up through the chimney. When the fires are in the proper condition, the dampers *c c'* are closed and the damper *g* is opened, and the hot air 50 from the furnace *a* passes up through the flue *e* and into the baking-oven through the openings *f f* at the top. The flue connecting the baking chamber with the chimney may be opened to create a draft through the oven, until the 55 oven has been brought to a proper degree of heat. The products of combustion from the fire *a'* pass into the hot-air chamber *h*, and the heat is transmitted through the wall of the

baking-oven into the oven itself, the heat being radiated from the interior surface of the 60 adjacent portion of the wall of the baking-oven. The goods to be baked are then placed in the baking-pans and the reel frame is revolved. The contents of the baking-pans are thus baked both by direct contact with the products of 65 combustion from the furnace *a* and by the radiation of heat from the furnace *a'*, through the wall of the baking-oven. By this system of introducing heat into the baking-oven a more perfect circulation of heat is secured, and 70 but little heat is wasted or allowed to escape, and as the heat is introduced either directly or by radiation into almost every part of the oven at the same time the oven is brought to the proper degree of heat in a comparatively 75 short time. The heated air in passing up the flue *e* heats the wall between that flue and the oven, and thus heat is transmitted through this intervening wall and radiated from all parts of the interior surface of oven-wall between the flue and the baking-oven. This radiation of heat from so large a part of the interior surface of the wall of the baking-oven, secures a very even distribution of the heat throughout the oven itself, and especially in 85 that part of the oven through which the baking-pans revolve.

By our invention the necessary width of the furnace and oven is greatly reduced, and thus economy of space is secured. The hot-air flue *e* may pass entirely across the top of the oven, as shown, or may open into the top of the oven only on one side.

What we claim as new, and desire to secure by Letters Patent, is—

95 In combination with a reel-oven, two furnaces below the oven, separated from it by an intervening wall, a flue passing from one of the said furnaces up and around the side or back of the oven and connected with the oven 100 by means of suitable openings at the top, and a hot-air chamber underneath the oven and connected with the other furnace, whereby the products of combustion from one furnace are introduced directly into the top of the 105 oven, and heat from both of the furnaces is introduced by radiation into the bottom and sides of the oven, substantially as and for the purposes set forth.

HENRY MCCOLLUM.

JOSEPH PARR.

ALEXANDER CRUMBIE.
